UNITED STATES PATENT OFFICE.

WILLIAM W. ROGERS AND FREDERICK H. DECKER, OF FRENCHTOWN, NEW JERSEY.

RAILWAY-SIGNAL.

1,305,239.

Specification of Letters Patent. Patented May 27, 1919.

Application filed October 13, 1917. Serial No. 196,440.

To all whom it may concern:

Be it known that we, WILLIAM W. ROGERS and FREDERICK H. DECKER, citizens of the United States, residing at Frenchtown, in the county of Hunterdon and State of New Jersey, have invented new and useful Improvements in Railway-Signals, of which the following is a specification.

This invention pertains to improvements in railway signal devices.

The invention aims primarily at the provision of an improved signal system including a track-side semaphore, a contact rail extending along the track rail adjacent the semaphore, a mechanism for energizing the contact rail in the danger position of the semaphore arm, and a train carried device adapted to be actuated when the train passes the semaphore location and the contact rail is energized to attract attention of the train crew to the position of the semaphore arm.

The invention aims particularly at the improvement of the mechanism for energizing the contact rail by providing a contact rod which is slidably mounted to engage against and disengage from the rail, to establish connection with and energize the latter in one position, and a simple and efficient link mechanism for actuating the contact rod by the movements of the semaphore arm.

A further object is the provision of a contact rod having an insulated section toward the contact rail and a hollow section extending from the insulated section toward the semaphore mast through which the conductor for energizing the insulated section is led, so that the conductor will be effectively protected from the weather, from meddling by an unauthorized person, or from accidental damage.

With these and other objects in view, we have embodied our invention in the preferred form illustrated in the drawings and described in the specification below.

In the drawings:—

Figure 1 is a side elevation of the device, and illustrates in fragmentary form a locomotive equipped with the train carried portion of the apparatus at the moment of passing the semaphore location.

Fig. 2 is a fragmentary top plan view in which are indicated diagrammatically the various electric circuits involved.

Fig. 3 is a longitudinal section through the contact rod indicating the structure in greater detail.

Referring to the drawings more particularly, a track-side signal semaphore adapted for operating the device is shown as of the commonly employed form having a vertical mast 1 and an arm mounted on the upper end of the mast for vertical swinging movement. The usual track rails are indicated by the numeral 3 and shown as carried by the cross tie 4.

In the present instance a supporting bracket 5 is secured to the lower end of the mast 1 as by bolts 6 and extends toward the rails 3. Pivoted to the other end of the bracket 5 is a bell-lever 7 having a vertical arm 8 and a horizontal arm 9. The lower end of the vertical arm 8 is pivotally connected to a contact rod 10 extending toward a contact rail 11 which in the present instance is disposed parallel to and between the track rails 3. Suitable insulating supports 12 are provided for the rail 11. Suitable bearings 13 are provided for the rod 10 whereby the latter is adapted for sliding movement to cause the end toward the rail 11 to engage against and disengage from the rail to establish connection with the latter. In the present instance the bearings 13 are mounted on one of the cross ties 4 which is prolonged toward the mast 1 for this purpose. In the present instance, also, the contact rod 10 extends through an opening 14 wherewith one of the track rails 3 is formed, but obviously the rod 10 might be bent to extend under the rail 3 if desired. Preferably the rod 10 has a short end section 15 toward the rail 11 for establishing contact with the latter, the other section 16 of the rod being hollow and having the section 15 mounted thereon by means of the insulating coupling 17. The horizontal arm 9 of the bell-lever 7 is pivotally connected to the lower end of an upwardly extending link 18 having similar pivotal connection at its upper extremity to the signal arm 2. The rod, lever, and link are so arranged that in the normal position of the signal arm, the section 15 of the rod is disengaged from the rail 11, while in the movement of arm 2 to danger position the section 15 will engage against and establish connection with the rail 11.

For energizing the rail 11 a source of electric energy indicated as a battery 19, may be conveniently located near the semaphore mast, and has one terminal connected with the track rails 3, in any suitable manner.

The other terminal of the battery 19 is connected to a conductor 20 which extends through the hollow section 16 of the rod 10 and is electrically connected with the end 5 section 15. A suitable housing may be provided when desired to protect the battery and the portion of the conductor 20 which extends beyond the hollow section 16, but is not shown in the present instance, as not 10 necessary for a clear understanding of the invention.

Extending from the under side of the locomotive are contact shoes 21 disposed on opposite sides of the locomotive so as to establish connection with the rail 11 in a movement of the locomotive in either direction. The shoes 21 are carried on suitable springs 22 in turn mounted on insulating supports 23 attached in any suitable manner 20 to a convenient portion of the train structure of the locomotive. Within the cab of the locomotive are provided a plurality of electric lamps 24, preferably of a red color to more readily attract attention, 25 and disposed in proximity to the positions usually occupied by the engineer and firemen respectively. One terminal of each lamp is grounded on the frame structure of the locomotive while the other terminal is 30 preferably connected with the shoes 21 so when passing a semaphore location where the semaphore arm is in danger position

the lamps 24 will be energized to attract the attention of engineer and firemen. Obviously any other desired signal devices, as 35 for instance a bell, might be included in the circuit with the lamps.

It is to be understood that the herein described preferred form of the invention constitutes only one of many comprised within 40 the spirit and scope thereof and the right is reserved to variations and departures therefrom falling within the latitude of the invention as defined by the claim.

What is claimed is:

The combination with a contact rail extending along a railway, of a hollow horizontal contact rod with one end in juxtaposition to said rail, said contact rod having an insulated end section extending toward 50 said rail, mountings for said rod whereby it is adapted for sliding movement, and an electric circuit including said insulated section of the contact rod and said rail, said circuit normally broken by a gap between said 55 insulated section of the contact rod and said contact rail and adapted to be completed by engagement of said section against said rail in one position of said rod.

In testimony whereof we affix our signatures.

WILLIAM W. ROGERS.
FREDERICK H. DECKER.
